PROTECTIVE EQUIPMENT FOR BANKS, ETC.

Charles J. Green, Oxford, Pa.

Application March 11, 1931, Serial No. 521,864

9 Claims. (Cl. 20—1.01)

The present invention relates to protective equipment for use in banks, post offices and similar places of business to protect life and valuables against hold ups.

5 The primary object of the invention is to provide a protective device for bank tellers and other custodians embodying a manually releasable bullet-proof shield normally retained in a concealed position and automatically moved into a 60 protecting position when released by the teller.

10 A further object is to provide a device of this character which may be economically constructed and readily installed in existing forms of bank counters and the like.

15 A further object resides in the provision of means whereby the protective shield when in its ejected position serves to uncover a battery of fire arms capable of being simultaneously discharged thru concealed openings.

20 A further object resides in the novel arrangement whereby the shield may be released by the knee of the operator while complying with the demands of the robber.

25 A still further object resides in the provision of a protective device of this character which when installed in a bank or the like may have the firearms associated therewith directed toward the entrance for preventing escape of the robbers.

30 Other objects and advantages of the invention will be apparent during the course of the following detailed description, taken in connection with the accompanying drawings forming a part of this specification and in which drawings:—

35 Figure 1 is a view in rear elevation of the device and showing the shield in its lowered position.

Figure 2 is a vertical section on the line 2—2 of Figure 1.

40 Figure 3 is a rear elevation showing the release means for the shield removed and parts broken away for disclosing details of construction.

Figure 4 is a view substantially similar to Figure 3 but showing the shield in its raised position.

45 Figure 5 is a fragmentary vertical section showing the shield in its raised position and uncovering openings thru which the firearms may be discharged.

50 Figure 6 is an enlarged fragmentary section on the line 6—6 of Figure 3.

Figure 7 is an enlarged fragmentary section on the line 7—7 of Figure 6.

55 In the drawings, and wherein similar reference characters designate corresponding parts throughout the several views, the letter A may designate a

suitable counter forming a portion of a teller's cage or the like and embodying the front wall 5 and top plate 6 and which may be formed of marble or any other suitable material. The letter B designates as a whole the improved protective device adapted to be associated with the counter A and operable by the teller or other person standing at the rear of the counter to frustrate any attempted hold up and the discharging of firearms if need be. 65

The device B comprises a pair of preferably tubular uprights or posts 7 extended thru openings formed in the top 6 just rearwardly of the counter wall 5 and suitably spaced apart to provide a window or opening thru which business 70 may be transacted. The posts 7 are preferably provided with threaded lower ends which are threaded into suitable floor sockets or plates 8 rigidly secured to the floor 9. The upper ends of the posts 7 are connected by an angle-shaped 75 head piece providing a horizontal flange 10 to which the upper ends of the posts are attached and a depending or vertical flange 11 which extends downwardly for a short distance over the front of the posts. Any suitable form of grille 80 or partitioning may extend along the counter from the sides of the posts 7.

The posts 7 are slotted at their confronting sides as at 12 and form guides receiving the side edges of a bullet-proof steel plate or shield 14 85 having movement thru a slot 15 provided in the counter top 6 between the posts 7. Arranged in each tubular upright 7 beneath the lower edge of the shield 14 is an expansion coil spring 16 which acts to throw the shield upwardly and close 90 the opening between the uprights when the trip means C is operated. These springs 16 are of such strength as to raise the shield with considerable force. Connected at one end to the lower edge of the shield 14 is a cable 17 having its opposite end secured to the floor 9 and this cable serves to limit upward movement of the shield and prevents the upper edge of the shield from striking the flange 10. This upward limited movement of the shield prevents strain upon the guide frame for the shield and will permit of the same being constructed of a lighter material than would ordinarily be required if the force of the shield is permitted to strike the flange 10. The upper portion of the shield plate 14 may be provided with a suitable slot 18 to receive a spring keeper 19 arranged at the rear side of the flange 11 whereby the shield is retained in a raised position. A suitable retracting cable 20 may be attached to the lower end of the shield and trained 105 110

over the pulley 21 secured to the floor 9 for lowering the shield against the action of the springs 16. The slot 15 in the counter top 6 may be closed by a suitable plastic filler such as putty or the like as shown at 22 in Figure 2 for closing the slot and concealing the shield when in its lowered position. If so desired, the slots 12 in the uprights 7 may also be closed in some suitable manner for presenting a neater appearance and concealing traces of the protective device.

The trip means C for releasing the shield 14 embodies a pair of standards 30 and 31 anchored to the floor 9 just rearwardly of the counter wall 5 and preferably midway between the uprights 7.

15 Horizontally guided in the standards 30 and 31 is a latch pin 32 the forward end of which is adapted to engage in any one of a number of vertically spaced openings 33 provided in the lower portion of the shield 14. This latch pin 32

20 when engaged in one of the openings 33 serves to retain the shield in its lowered concealed position against the action of the elevating springs 16. The upper portion of the standard 30 is rearwardly offset as shown in Figure 2 and has pivotally

25 connected thereto an L-shaped lever 34 which extends rearwardly and upwardly toward the rear of the counter. The forward downturned end of the lever 34 is connected by a pin and slot connection 35 to the rear end of the latch pin 32

30 whereby upon upward swinging of the lever 34 the latch pin will be retracted from holding engagement with the shield 14 and allow the shield to be raised by the springs 16. Connected to the rear end of the lever 34 is a horizontally disposed

35 knee bar 36 having attached to each end thereof adjustable tensioning springs 37, the lower ends of which are anchored in the floor 9. These springs 37 act to normally exert a downward pull on the lever 34 and force the latch pin 32 into

40 one of the openings 33. When desiring to release the shield 14, the operator merely raises his knee against the bar 36 and retracts the latch pin 32 allowing the shield to be raised by the springs 16 and retained in a raised position by the spring 45 latch 19.

Secured to the lower edge of the shield 14 is a latch 38 for operating a suitable electric switch 39 and this switch may be connected for operating suitable signals or any other desired protective apparatus upon release of the shield 14. Mounted in any preferred manner beneath the counter top 6 is a shelf 40 and which shelf is arranged just rearwardly of the shield 14 preferably parallel to the top 6. End blocks 41 arranged at 55 each end of the shelf 40 serve as spacers for spacing the shelf below the top 6. Mounted in spaced relation upon the upper side of the shelf 40 as by straps or other suitable attaching means 42 is a plurality of firearms 43, the barrels of which are directed toward the shield 14. The upper portion of the front wall 5 is provided with a number of openings 44 which align one with each of the barrels of the firearms 43 and these openings may be closed by suitable plugs 45 serving to conceal the openings and presenting a smooth appearance to the face side of the wall.

The firearms 43 are intended to be simultaneously operated by a person standing at the rear of the counter and the operating or discharging means for the firearms embodies a cross bar 46 slidably guided at its ends upon suitable pins 47 projecting rearwardly from the end blocks 41. This cross bar 46 has attached to its central portion an operating rod 48 which extends rearwardly to a point adjacent the rear edge of the top 6 and

may have a suitable handle at its rear end to be readily grasped by an operator for exerting a rearward pull upon the rod. Connected to each end of the cross bar 46, inwardly of the end block 41 is an adjustable coil spring 49, having their opposite ends attached to the block 41 whereby the cross bar is normally urged toward the end blocks. Connected to the front side of the cross bar 46 is a series of elongated hooks 50 having downturned ends 51 adapted to engage the triggers of the firearms 43 and exert a pull upon the triggers upon rearward movement of the cross bar. The hooks 50 may be adjustable in any preferred manner and in the example shown, the hooks are provided with threaded ends which are threaded into the cross bar and this arrangement permits proper positioning of the downturned ends 51 with respect to the triggers of the firearms.

As will be observed in Figure 2, when the shield 14 is in its lowered position, the upper portion of the shield confronts the firearms 43 and serves as a barrier should the firearms be accidentally discharged. In Figures 4 and 5 however, it will be seen that when the shield is raised that the shield is out of confronting relation to the firearms and will permit the bullets to pass thru the openings 44 when the firearms are discharged by a rearward pull upon the rod 48. The plugs 45 closing the openings 44 are of course of such nature as to be readily ejected by the force of the bullets passing thru the openings.

Thus it will be seen that a device of this character has been provided which may be readily installed in various places with comparatively little alteration to the counter. It will also be apparent that a novel arrangement has been disclosed whereby the shield is automatically released by one's knee thru a slight upward pressure upon the horizontal trip rod. It will also be apparent that a novel arrangement has been provided whereby a plurality of firearms may be simultaneously discharged, and an arrangement whereby the shield serves as a barrier extending across the firearms so as to prevent damage thru accidental discharging of the firearms.

Changes in detail may be made to the form of invention herein shown and described, without departing from the spirit of the invention or the scope of the following claims.

I claim:

1. In protective equipment of the class described, a vertically guided shield, trip means for retaining the shield in a concealed position, and a firearm confronted by the shield when the shield is in its concealed position.

2. In protective equipment of the class described, a vertically guided shield, means for moving the shield to a protective position, trip means for normally retaining the shield in a concealed position, a plurality of firearms confronted by the shield when in its concealed position, and means for simultaneously firing the firearms.

3. In combination with a counter including a top and a front wall, said front wall having openings therethru, a plurality of firearms mounted beneath the top wall, means for simultaneously firing the firearms, and a shield vertically movable thru the top wall between the firearms and the openings in the front wall, said shield when in a lowered position forming a barrier between the firearms and said openings and when in a raised position being disposed above the firearms.

4. In protective equipment of the class described the combination with a counter includ-

ing a top and a front wall, of a shield guided for vertical movement thru the top at the rear of the front wall, a shelf mounted beneath the top rearwardly of the shield, a plurality of firearms mounted upon the shelf and having the barrels thereof aligning with openings provided in the front wall, said shield when in a lowered position having its upper portion confronting the firearms, and means for simultaneously firing the firearms, said shield when in a raised position being out of confronting relation to the firearms.

5. In combination with a counter including a top and a front wall, said front wall having openings therethru, a shelf mounted below the top, a plurality of firearms fixed upon the shelf and aligning with said openings in the front wall, a movable cross bar mounted on the shelf, a series of hooks carried by the cross bar for independently engaging the triggers of the firearms, a pull rod 20 for actuating the cross bar for simultaneously discharging the firearms, and a protective shield forming a barrier between the firearms and openings in the front wall when the shield is in its normal retracted position.

25. 6. In protective equipment the combination with a counter including a top and a front wall, said front wall having openings therethru, a shelf mounted below the top, a series of firearms mounted upon the shelf in aligning relation with the openings in the front wall, a cross bar extending across the rear side of the shelf and movable toward and away from the shelf, spring means normally urging the cross bar toward the shelf, a series of hooks threaded into the cross bar one 35 for each of the firearms, said hooks having their free ends engageable with the triggers of the firearms, and a pull rod connected to the cross bar and extending rearwardly therefrom for simultaneously discharging the firearms upon a rearward pull upon the rod.

7. In protective equipment the combination with a counter including a top and a front wall, a shield guided for vertical movement thru the top, firearms normally confronted by the shield when in its lowered position, means for firing the firearms, and an electric switch closed upon upward movement of the shield.

8. In protective equipment, the combination with a counter including a substantially horizontal top, and a guard shield movable from a non-protective position to a protective position above the counter top, of means to move said shield to said protective position, and means to normally retain said shield in a non-protective position including a latch, a horizontally disposed vertically movable bar extending longitudinally of the counter, spaced a short distance below and near the rear of the counter top, and motion transmitting means between the bar and latch to release the latch upon upward movement of the bar.

9. In protective equipment, the combination with a counter including a substantially horizontal top, and a guard shield movable from a non-protective position to a protective position above the counter top, of means to move said shield to said protective position and means to normally retain said shield in a non-protective position including a latch, a horizontally disposed vertically movable bar extending longitudinally of the counter, spaced a short distance below and near the rear of the counter top, motion transmitting means between the bar and latch to release the latch upon upward movement of the bar, spring means yieldably retaining the bar in a position spaced below the counter top but permitting it 135 to be raised toward said top, and means for adjusting the action of the spring so that varied pressure upon the under side of the bar will be required to move it upwardly.
